UNITED STATES PATENT OFFICE

THURSTON MCGILL, OF CHICAGO, ILLINOIS

DISH BASKET

Application filed October 2, 1926, Serial No. 139,125. Renewed March 31, 1930.

This invention relates to dish baskets and more particularly to dish and silverware receiving containers for effecting the drying thereof, although it may be employed to facilitate scalding and rinsing of the utensils prior to effecting the natural drying thereof.

It contemplates more especially the provision of a perforated basket body capable of association with a skeleton frame to define a plurality of compartments capable of receiving numerous utensils therein for effecting the rinsing and drying thereof.

One object of the present invention is to simplify the construction and improve the 15 operation of devices of the character mentioned.

Another object is the provision of a skeleton frame capable of ready association with a perforated basket body to confine a plurality of compartments therein.

Still another object is the provision of a rigid skeleton frame which is externally secured within a basket body which is reinforced thereby.

25 A further object is the provision of a plurality of graduated partitions co-operating with the basket body to define individual partitions thereon to accommodate a plurality of implements of various construction.

30 A still further object is the provision of a reinforcing strip in association with the skeleton frame to constitute a shallow silverware compartment.

Still a further object is the provision of 35 a plurality of partitions graduated in height which cooperate with the basket to define a plurality of compartments therein capable of receiving implements of various sizes, there being a shallow compartment capable of receiving silverware therein, whereon other dishes may be supported with convenience without impairing the structure thereof.

Other objects and advantages will appear 40 from the following description of an illustrative embodiment of the present invention.

In the drawing:

Figure 1 is a plan view of a device embodying features of the present invention;

50 Figure 2 is a sectional view taken substantially along line II—II of Figure 1;

Figure 3 is a sectional view taken substantially along line III—III of Figure 2;

Figure 4 is a perspective view of a skeleton frame which is capable of ready association with the basket to define a plurality of compartments therein; and

Figure 5 is a perspective view of a connecting rod which enables the skeleton frame to be rigidly fixed to the basket.

The structure selected for illustration comprises a basket 10, including a substantially rectangular rim 11 to which looped extremities 12 of interwoven wires 13 and 14 are secured in any suitable manner to constitute a perforate basket body. It is to be noted 60 that the transverse wires 14 terminate in angularly disposed end portions 14' which are secured to the rim near the corners to increase the rigidity thereof.

To enable dishes and other utensils to be 70 conveniently arranged therein to effect the drying thereof, a skeleton frame 15 is disposed within the basket to define compartments therein. The skeleton frame 15 comprises a substantially rectangular frame 16 75 having substantially U-shaped members 17 secured thereto to define partitions of different height 18 and 19 which are maintained in rigid relation therewith by welding, soldering, or otherwise effecting a joinder therebetween. Division wires 20 are secured to the members 17 intermediate the extremities thereof to retain a plurality of dishes in the receiving compartments defined thereby.

It is highly desirable to provide a silverware compartment which will retain such utensils against displacement and permit the 85 convenient disposition of other implements thereon which ordinarily are too large or irregular to be disposed in the compartments described hereinabove. To accomplish this end, a strip of metallic material 21 having twisted end portions 22, is secured in any suitable manner to the rim 16 at its extremities 90 22 to constitute a reinforcement therefor and also to define a shallow compartment with a wall of the basket 10.

The skeleton frame 15 is thus assembled in its entirety prior to its disposition in the basket 10 with the rim member 16 thereof ex- 100

tending internally around the lower portion of the basket structure to serve as a reinforcement for the side walls 23 and bottom 24 constituting the perforate basket body. Intersecting wires 25 are externally associated with the bottom of the basket body 10 in diagonal relation, their end portions being curled or looped to form eyes 26 for connection with the corners 17 of the rim members 16 to which they are externally fixed in the usual manner. The connecting wires 25 are each provided with spaced depressions 28 which serve to elevate the bottom 24 from the surface upon which the basket is disposed. The interior skeleton frame 15, composed of the partition 18, co-operates with the adjacent side wall 18' of the basket body 10 to form an end compartment 29 within which large dishes may be nested. Moreover, the partition 18, together with the partition 19, define a compartment 19' wherein various size dishes may be confined, these dishes being preferably of less size than the dishes confined in the end compartment 29. The partition 19, which is disposed in confronting relation with the flat strip 21, provides a compartment 21' therebetween to conveniently receive bowls or other irregular articles. Further, the flat strip 21 co-operates with the adjacent end wall 22' of the basket body 10 to define a shallow compartment 23' within which silverware or other utensils may be flatly disposed to receive cups and glasses thereon without interfering with the partition strip 21 which incidentally reinforces the entire structure, thereby materially increasing the capacity of baskets of standard size.

It is to be noted that the graduated partitions avoid interference incidental to the removal of the kitchen ware or cooking utensils from the various compartments, since the flat narrow strip 21 materially rigidifies the basket body and also enables the confinement of large platters in the compartments 21' and 23', this being accomplished by reason of the solid metallic strip 21 which properly confines silverware therein for convenient removal therefrom in that the shallow silverware compartment serves to retain silverware in a predetermined position and permits compartments 21' and 23' to be merged together for receiving large platters or irregular objects therein. It is thus apparent that silverware is capable of accommodation without preventing the disposition of large kitchen ware within the basket.

With the arrangement of parts above described, a novel dish basket or drier has been provided which may be assembled in an expeditious and inexpensive manner in that the skeleton frame is capable of complete assembly prior to the association thereof with the basket body, it only being necessary to secure external connecting rods thereto which serve as a support for the entire structure. The

skeleton frame 15 is preferably associated with the basket body 10 by means of wire staples 27' of any appropriate construction, thereby effecting a rigid joinder of the walls of the basket with the skeleton frame which serves to rigidify and render the structure more durable.

Various changes may be made in the embodiment of the invention herein specifically described without departing from or sacrificing any of the advantages of the invention as defined in the appending claims.

I claim:

1. In a device of the class described including a basket structure, a partition framework assembled as a single unit for confinement in the basket body, said partition framework comprising a plurality of partitions graduated in height cooperating with the basket structure to divide the basket structure into a plurality of compartments, one of said partitions being formed of a flat strip of material, and means for connecting the partition framework to the basket structure.

2. In a device of the class described including a basket structure, an angular frame confined in the basket structure, members extending diagonally across the bottom of the basket at the under side thereof and having end portions connected to the corners of the frame, partitions of different height each formed from a member bent substantially U-shaped with end portions connected to opposite sides of the frame, and a partition member formed from a separate flat strip of material and having its end portions connected to said opposite sides of the frame, the intermediate portion of said last mentioned partition being disposed with its flat side extending in a substantially vertical plane.
